SCISSORS AND SHEARS.

1,293,122.

Specification of Letters Patent.

Patented Feb. 4, 1919.

Application filed April 3, 1917. Serial No. 159,416.

To all whom it may concern:

Be it known that I, EDWARD KOEHLER, a citizen of the United States, residing at Bridgeport, county of Fairfield, State of Connecticut, have invented an Improvement in Scissors and Shears, of which the following is a specification.

This invention relates generally to scissors and shears and more especially to the class 10 of scissors and shears in which the bows are provided with covers made of leather, rubber or textile material which has heretofore been wrapped about the bows and in some instances the shanks and has been secured thereto by stitching or cementing it in place. In some instances the inner sides of the bows only have been covered and in other instances the bows and sometimes the shanks or a portion of them have been 15 covered. These modes of covering the bows have been more or less unsatisfactory on account of the greatly increased cost of production and owing furthermore to the fact that the covers frequently became partly or 20 wholly loosened in use and were unsightly in appearance. So far as I am aware all scissors and shears heretofore placed on the market, whether or not the bows were covered, have been provided with closed 25 bows that is, bows in which the finger and thumb openings were entirely surrounded by metal disposed in continuous form, that is without a break.

My present invention has for its object to 30 provide scissors and shears having what I will term open bows, that is bows in which the finger and thumb openings are not surrounded by metal disposed in continuous form but in which each bow is provided 35 with an opening, which may be either on the inner or outer side as may suit the taste of the manufacturer or best meet the requirements of the trade, and to provide in connection with these open bows tubular 40 covers which are adapted to be slipped on over the bows and may cover the whole or portion of the shanks as may be required.

In the accompanying drawing forming a 45 portion of this specification Figures 1 and 2 are elevations illustrating various forms of the invention, and Fig. 3 is a view of one of the covers, detached.

10 denotes the blades of a pair of scissors

or shears, 11 the shanks, 12 bows formed continuous with the shanks and each provided 55 with a relatively narrow opening 13, and 14 tubular covers which are adapted to be slipped on over the bows and to partially or wholly cover the shanks as preferred. These covers may be made of leather, rubber or 60 textile material as preferred, and are made of any suitable shape or size to meet the special requirements of different sizes and styles of scissors and shears. The covers are preferably closed at their outer ends as at 65 15, but this is not essential. The covers may be detachable, or self retaining or may be cemented in place as preferred.

In Fig. 1, I have illustrated a form in which the relatively narrow openings are 70 upon the inner sides of the bows and the ends of the bows are recurved outward and adapted to abut, as at 16, and form a stop to limit the closing movement of the blades.

In Fig. 2, I have illustrated a form in 75 which the relatively narrow openings are upon the inner sides of the bows, but the ends of the bows, instead of being recurved inward as in Fig. 1, are recurved outward away from each other and the recurved portions are so shaped that their inner sides will abut, as at 19, and form a stop to limit the closing movement of the blades.

The operation of attaching the covers will be obvious. The covers are simply passed 85 over the free ends of the bows and slipped in place and may or not be cemented or otherwise secured in place as preferred.

It will be observed that in both Figs. 1 and 2 the bows are bent sharply out from 90 the shank contiguous to the opening 13, by a pronounced curve. This sharply bent or pronounced curved portion assists the recurved portions of the bows to prevent slipping of the tubular covers, thereby aiding 95 to retain said covers in place.

Having thus described my invention I claim:—

An improvement in scissors and shears comprising pivotally connected blades each 100 having a shank and a curved bow, a beveled shoulder being formed at the juncture of the blade and shank, the shank being enlarged contiguous to the shoulder, the extremity of the bow being recurved, and a 105 tubular cover for the bow and shank, said

cover having an enlarged beveled end complementary to said beveled shoulder, the other end being closed to cover the extremity of the bow, the extremity of the bow being spaced from the body thereof to permit the cover to be slipped on the bow and to pass said extremity, said bow having a pro-

nounced curve to aid in retaining the cover in place, the recurved portions of the bows being positioned to abut when the blades are 10 in closed position.

In testimony whereof I affix my signature:

EDWARD KOEHLER.
